R. A. STEPS

METHOD OF MAKING SCREEN PIPE

Filed March 30, 1923

Robert A. Steps
INVENTOR

UNITED STATES PATENT OFFICE.

ROBERT ALEXANDER STEPS, OF LOS ANGELES, CALIFORNIA.

METHOD OF MAKING SCREEN PIPE.

Application filed March 30, 1923. Serial No. 628,945.

To all whom it may concern:

Be it known that I, ROBERT ALEXANDER STEPS, a citizen of the United States, residing at Los Angeles, in the county of Los Angeles and State of California, have invented a new and useful Method of Making Screen Pipe, of which the following is a specification.

My present invention relates to an improved modification of the more general invention shown in my Patents No. 1,207,808 and 1,207,809.

The object of the present invention is to simplify the manufacture of screen pipes of the kind involved, and to increase their screening capacity at the same time that the cost of manufacture is reduced.

It is understood that the screen pipes to which this invention applies is used in oil or water wells for the purpose of holding the sand and gravel out, while the fluid passes through and is pumped to the surface of the earth by proper pumps installed in the well. If the natural pressure on the fluid is sufficiently great the pump may of course be dispensed with as the fluid will then rise in the well under its own pressure.

Screen pipes of this sort are made of heavy steel or iron pipe with suitable screening apertures formed therein. The pipe comes in sections of various lengths, often about 20 ft. each, and from 4 to 16 inches in diameter, and these sections are screwed together to give the required length of screen corresponding with the thickness of the strata in which the desired fluid is found.

The tendency of course is for the sand and gravel to come through the screen with the fluid, but this is undesirable for many reasons, and on this account care must be exercised in so forming the screening apertures that they hold back the sand effectively without retarding the flow of the liquid.

It is this result which my invention accomplishes very nicely. The screening apertures formed in accordance with my invention are narrower on the outside of the pipe than they are on the inside, so that the external sands are held out right at the outside surface of the pipe, but if any particles get past the narrower outside portion of the slot they pass right through the slot without sticking or clogging therein, as the slots which I produce are wider toward the inside than they are toward the outside of the

pipe where the real excluding action of the sand is effected.

Claim for the screen pipe herein described is made in my copending application No. 59,585, filed September 30, 1925. 60

For the purpose of increasing the screening capacity without increasing the cost of manufacture of this kind of screen I have grouped my slots into pairs, because by my new method of operation I am now able to 65 produce a pair of slots as easily as a single slot could be produced, so that the added screening benefit of the extra slot is obtained without any increase in cost.

The broad steps of this invention are 70 pointed out in the claims. These steps can be performed in various ways, and I will now describe what I regard as the preferred way or ways.

In the accompanying drawings Fig. 1 75 shows a way of carrying out the first step in my invention, which consists in forming pairs of slots in the pipe preferably with slotting saws mounted on a common arbor. Fig. 2 is a side view indicating the shape of 80 the slotting saws diagrammatically. Fig. 3 shows a way of carrying out the second step in my invention whereby the slots are formed so as to be narrower toward the outside of the pipe than they are at the 85 inside of the pipe. Figure 4 is a side view inside of the pipe. Figure 4 is a side view of the tool shown in Fig. 3. Fig. 5 shows another way of carrying out the second step of my invention, and Fig. 6 is a side view of the tool shown in Fig. 5. Fig. 7 shows a 90 short piece of the screen pipe finished in accordance with my invention, and Fig. 8 is a transverse section of same.

By mounting the usual slotting saws 1 close together on the common arbor 2, Fig. 95 1, a pair of slots 3 may be cut in the wall of the pipe 4, a bar 5 separating the slots in the pair. At the end of this first step in my method the side walls of the slots are substantially parallel, and the slots are 100 as wide on the outside of the pipe as they are on the inside of the pipe. Figs. 3 and 4 show a roller 6 adapted to bridge across the pair of slots, the edges 7 of the roller being spaced sufficiently apart to rest on the 105 edges of the slots which are furthest from each other. By any suitable means, this roller may be pressed down on the pipe at the same time that it is rolled back and forth along the length of the slots, and 110

as this continues these edges of the slots are pressed toward each other.

In practice I use a pneumatic or hydraulic cylinder for producing the required pressure on the roll, and in view of the concavity 10 of the roll the above operation is very nicely accomplished. In fact, the number of strokes back and forth along the slots, determines the degree to which the 10 lips are pressed toward each other, and if narrower slots are desired it is merely necessary to give the roller a few more strokes before the pressure is released.

At the end of this rolling operation the 15 slots are seen to be narrower at the outside of the pipe than they are at the inside.

This gives the effective screening qualities which have already been described.

Figs. 5 and 6 show another tool 11 in 20 the nature of a chisel, which may be used in place of roller 6. In this case the chisel may be struck with any sort of a hammer on the chisel head 12 and the opposite edges of the slot will thus be forced or pressed 25 toward each other.

After completing one pair of slots the operation is repeated as often as desired until the entire section of pipe is thus 30 perforated. The spacing and arrangement 35 of the slots may vary considerably according to conditions under which the screen is expected to operate, and also according to the desires of the manufacturer or user. The arrangement shown in Figs. 7 and 8 however, is found practicable, but need not be followed, and the slots can of course be formed transversely, or any other way

in the pipe, in place of longitudinally as I have shown them, as my invention is 40 equally applicable whether the slots run lengthwise of the pipe or otherwise. It is obviously important that the slots in each pair should be comparatively close together compared with the distance between neighboring pairs of slots, as this gives the increased screening area without correspondingly weakening the pipe.

I claim.

1. The method of making screen pipe consisting in slotting the pipe with pairs of 50 slots, the slots in each pair being close together compared with the distance between pairs, and then simultaneously forcing the edges of the slots on the outside of the pipe furthermost from each other in any 55 pair, toward each other so as to make each slot narrower on the outside of the pipe than on the inside.

2. The method of making screen pipe consisting in slotting the pipe with pairs of 60 slots, the slots in each pair being close together compared with the distance between pairs, and then applying a roller adapted 65 to bridge across the edges of the slots furthermost from each other in any pair, and moving said roller lengthwise of the slots under pressure so as to force the last 70 said edges of the slots toward each other to make each slot narrower on the outside of the pipe than on the inside.

Signed at Denver, in the county of Denver and State of Colorado, this 26th day of March, 1923.

ROBERT ALEXANDER STEPS.
